UNITED STATES PATENT OFFICE.

MORRIS LEVIT, OF CHICAGO, ILLINOIS, ASSIGNOR OF ONE-HALF TO MOSES WEINBERG, OF SAME PLACE.

DESIGN FOR A SCENIC BURNER.

SPECIFICATION forming part of Design No. 27,156, dated June 1, 1897.

Application filed January 11, 1897. Serial No. 618,886. Term of patent 3½ years.

To all whom it may concern:

Be it known that I, MORRIS LEVIT, a citizen of the United States, residing at Chicago, in the county of Cook and State of Illinois, have 5 invented and produced a new and original Design for a Scenic Burner, of which the following is a specification, reference being had to the accompanying drawing, showing a part thereof.

10 The accompanying figure is a view of my design, which is for a scenic burner.

The leading feature in my design consists in a raised and corrugated outer surface on the four sides of a square box, the outlines 15 of which, when viewed from any direction, will represent tiers of logs, each tier placed transverse to the adjoining one, and the whole having the appearance of a solid pile. Each of the four outer surfaces of the box has a 20 series of raised semicircular ornamented and

corrugated surfaces of such a shape and size as to represent the side of a log with the bark and knots on, alternating with a row of circular protuberances representing the ends of logs placed in a tier at right angles thereto. 25 The box is smooth on the inside and provided with a plain surface.

What I claim as my invention is—

The design for a scenic burner herein shown and described, the same comprising a square 30 box with the four outer surfaces so shaped, raised, corrugated and ornamented as to represent a solid pile of logs placed in a series of tiers at right angles to each other, the inner surface of the box being smooth and plain. 35

MORRIS LEVIT.
